UNITED STATES PATENT OFFICE.

WILLIAM I. F. HARDEN, OF HARTFORD, KANSAS.

CHIMNEY-PROTECTOR.

SPECIFICATION forming part of Letters Patent No. 726,160, dated April 21, 1903.

Application filed May 17, 1902. Serial No. 107,852. (No model.)

To all whom it may concern:

Be it known that I, WILLIAM I. F. HARDEN, a citizen of the United States, residing at Hartford, in the county of Lyon and State of Kansas, have invented certain new and useful Improvements in Chimney-Protectors; and I do hereby declare the following to be a full, clear, and exact description of the invention, such as will enable others skilled in the art to which it appertains to make and use the same.

This invention relates to chimney-protectors and is in the nature of an improvement on my Patent No. 469,069, issued to me February 16, 1892.

The object of my invention is to provide a simple, durable, and efficient chimney-protector in such form that it will be convenient for shipment and can be readily attached to chimney-tops of varying sizes and shapes by a person of ordinary intelligence without having to remove any bricks or otherwise disturb the chimney-top.

Further objects and advantages of the invention will appear in the following description, and the novel features will be particularly pointed out in the appended claims.

The essence of the invention resides in the novel and peculiar arrangement and combination of parts, including their construction, and in the accompanying drawings, representing the preferred embodiment of my invention—

Figure 1 is a perspective view of my protector complete, applied in the operative position to a chimney-top. Fig. 2 is a modification showing different means for securing my protector to a chimney. Fig. 3 is a detail view of one of the bands. Fig. 4 is a detail view of means for adjusting the protector to a chimney.

Similar reference-figures denote similar parts throughout the several views of the drawings.

In practice I provide a series or plurality of metal bands 1, bent and applied to a chimney-top at points above, on, and below the bulge or flange thereof, in such a manner as to form three continuous horizontal bands encompassing the chimney-top at said points. These bands are preferably of such width as to cover the joint between two courses of brick

and are provided with outstanding ears or flanges 2, having apertures 3, through which pass screw-bolts 4, by means of which the bands may be tightened or loosened, as desired. I also employ an additional series of four or more metal plates or bands 5, bent so as to form a hook on one end of each band, and this hooked portion of the band is hung over the chimney-top with the shorter of its vertical arms extending down inside the chimney. The other and longer arms of the hooked band extend downwardly outside the chimney, being bent to conform to the conformation thereof, and are secured by rivets 6 or other means to the lowermost of the encompassing horizontal bands. These four vertical bands are placed one upon each side of the chimney-top and besides being secured to the uppermost and lowermost of the horizontal bands are secured or riveted to the central encompassing band, thus insuring additional security. Where desirable, the upper of the encompassing bands may be provided with a series of angle-plates, either cast 75 integral therewith or secured by rivets or other means, and it will be seen that the combination and arrangement described forms a frame or hood surrounding the chimney-top of exceptional strength, said frame or hood 80 being practically an integral structure. The adjusting means shown are preferably arranged alternately of the vertical band on the side of the chimney-top on which said adjusting means are formed, as seen in the 85 drawings.

In the modification shown by Fig. 2 wire staples and coupling-plates instead of screw-bolts are used to secure the protector to the chimney-top. It is obvious that various 90 other minor changes may be made in my invention without departing from the spirit thereof, and I wish it to be understood that I do not limit myself to the details as shown and described in this application.

It will be further apparent that the bands or strips used in the construction of my chimney-protector, being formed or cut direct from sheet metal in straight strips of desired lengths, which are then punched, ready for 100 bending by pliers or other means and application to chimneys of various shapes and

sizes, are in extremely convenient form for shipment, as a large number can be nested in comparatively small space.

Having thus described my invention, what I claim as new, and desire to secure by Letters Patent, is—

1. In a device of the character described, the combination of a plurality of metal strips or bands surrounding and secured to a chimney-top, those forming connections between others being each formed of a lower and an upper step-like portion, means securing said strips together so as to form a frame or hood, and means for adjusting said hood or frame to the chimney-top, substantially as set forth.

2. In a chimney-top protector, the combination of the horizontal and vertical bands forming a hood or frame, means for adjusting said hood or frame to a chimney-top, and means for securing the same thereto, substantially as set forth.

3. In a chimney-top protector, the combination of vertical and horizontal bands forming a frame or hood, and means for adjusting said frame or hood to a chimney-top, the upper said horizontal bands being provided with a series of angle-plates adapted to clamp the chimney-top, substantially as set forth.

4. In a chimney-top protector, the combination of series of bands adapted to be applied to a chimney, those effecting connection between others being each formed of a step-like portion, substantially as set forth.

5. In a chimney-protector, the combination of a series of bands adapted to be applied to a chimney, those effecting connection between others being each formed of a step-like portion, and means for effecting the adjustment of said parts to the chimney, substantially as set forth.

6. In a chimney-protector, the combination of a series of bands adapted to be applied to a chimney, those effecting connection between others being each formed of a step-like por-

tion, and one or more of the connected-up bands comprising sections adapted to be adjustably connected together, substantially as set forth.

7. In a chimney-protector, the combination of a series of bands adapted to be applied to a chimney, those effecting connection between others being each formed of a lower and an upper step-like portion, substantially as set forth.

8. In a chimney-protector, the combination of a series of bands adapted to be applied to a chimney, those effecting connection between others being each formed of a lower and an upper step-like portion, and one or more of the connected-up bands comprising sections adjustably connected together, substantially as set forth.

9. In a chimney-protector, the combination of a series of bands adapted to be applied to a chimney, those bands effecting connection between others being each formed of a lower and an upper step-like portion, with the upper or free end portions of said connecting-bands bent or extended downwardly to engage the flue-surface of the chimney, substantially as set forth.

10. In a chimney-protector, the combination of a series of bands adapted to be applied to a chimney, those bands effecting connection between others being each formed of a lower and an upper step-like portion, with the upper or free end portion of said connecting-bands bent or extended downwardly into the flue-surface of the chimney, and one or more of the connected-up bands comprising sections adjustably connected together, substantially as set forth.

In testimony whereof I affix my signature in presence of two witnesses.

WILLIAM I. F. HARDEN.
